UNITED STATES PATENT OFFICE.

CHARLES A. ROSIER, OF NEW YORK, N. Y.

HYDROCARBON BURNER.

Application filed July 9, 1924. Serial No. 724,964.

This invention relates to hydrocarbon burners, and more particularly to means for automatically controlling the operating of hydrocarbon burner equipment installed in 5 heat generators such as boilers or tempering furnaces and the like.

An object of the invention is the provision of means of the character described for economically regulating the combustion 10 of the fuel to vary with the load requirement.

Another object of the invention is the provision of an automatic control means for hydrocarbon burner boiler equipment which 15 is simple in operation, and effective to keep the steam pressure of a boiler practically constant and to regulate the said equipment for conditioning and feeding the fuel to obtain highly efficient combustion.

20 A further object of the invention is the provision of means of the character described, which operates with minimum attention and which is composed of few and simple parts that are easy to install and 25 relatively cheap to manufacture.

Other objects of this invention will in part be obvious and in part hereinafter pointed out.

Certain features herein shown and 30 described are shown, described and claimed in my co-pending application Serial No. 585,337, filed in the United States Patent Office on the 31st day of August 1922, and Serial No. 724,963 filed July 9th, 1924, and 35 accordingly not claimed herein.

With the above exception, the invention accordingly consists in the features of construction, combinations of elements and arrangement of parts which will be exemplified in the construction hereinafter 40 described and of which the scope of application will be indicated in the following claims.

In the accompanying drawings, in which 45 is shown one of the various possible illustrative embodiments of this invention,

Fig. 1 is a vertical section of a hydrocarbon burner equipped with automatic control means embodying this invention;

Fig. 2 is a front elevational view of the 50 valve and damper control means shown in Fig. 1; and

Fig. 3 is a side elevational view of equipment shown in Fig. 1 with automatic control means by steam boiler pressure.

55 The control device embodying my invention may be installed to co-operate with any

hydrocarbon burner equipment and is shown in the accompanying drawing as applied to the type of carbon burner fully described in my said co-pending application Serial No. 585,337 filed August 31st, 1922.

Referring in detail to the drawing, 10 denotes a fragmentary portion of a boiler having a furnace combustion chamber 10^a to which is attached the hydrocarbon burner 65 equipment 11 by any suitable means such as frame 12.

The hydrocarbon burner equipment 11 comprises, as is seen from Fig. 1, an atomizing and spraying burner portion 13 and a 70 fuel vaporizing and preheating portion 14 disposed therebelow, the burner outlet end of portion 13 being adapted to communicate with portion 14 by means of a passage 15.

75 The portion 14 comprises a tubular member 16 divided into two compartments 17 and 18 by a baffle plate 19 extending longitudinally of the member 16. The lower compartment is adapted to vaporize and permit the expansion of the fuel oil entering at the 80 front end 21 thereof, from a passage 22, which connects with the outlet side of an oil control angle valve 23, the latter receiving fuel from an oil storage tank (not 85 shown) through a pipe 24. Valve 23 is controlled in the usual manner through the rotation of the valve stem 23^a. Means for draining the lower compartment is provided at 25, which connects with discharge pipe 25^a which may be opened and closed in any 90 suitable manner.

95 The upper compartment 18 serves to preheat the vaporized fuel and is provided at its front end with an upwardly extending passage 26 for leading the oil vapors into the inlet side of a mixing valve 27 from which they emerge through opening 27^a into a mixing chamber 28. The valve 27 controls the flow of the oil vapors in the usual manner through the rotation of the valve 10 stem 27^b. To condition the oil vapors for most efficient combustion, suitable amounts of steam or compressed air are provided from a source (not shown) through a pipe line 49 and injected into said vapors. For the purpose of controlling the supply of steam or air, there is installed in pipe line 49 a valve 29 having the outlet side thereof connecting with a passage 30 which extends vertically upward from said valve 27, the 110 lower end of said passage 30 joining an annular passage 31 formed in said valve 29.

Said passage 31 leads into the chamber 28 through openings 31^a, so that an intimate mixture of the oil vapors and steam or compressed air is obtained upon emerging of 5 the mixture from the burner outlet 32.

Valve 29 is controlled by rotating valve stem 29^a the latter being mounted to turn in the valve body 29^b on left-handed threaded connection having a coarse pitch; the purpose of which will hereinafter appear.

It is clear from the drawing that part of the heat generated in the furnace serves to heat up tube 16, particularly by reverberation through the passage 15. For effectively 15 and positively controlling the temperature to which the oil is subjected during the vaporization and preheating in tube 16, I provide sector-shaped dampers 33, 34 disposed horizontally over the tube 16 between 20 the latter and the passage 15. The dampers are movably mounted to provide a variable opening 35 between them wherethrough heat is transmitted to impinge on the tube 16, said dampers 33, 34 being respectively sup-

25 ported from the upper end of arms 36, 37, which are secured at their opposite ends respectively to rock shafts 38, 39, having operating levers 40, 41. The dampers 33, 34 may be rocked toward or away from each 30 other to vary the size of the opening 35 thereby regulating the degree of heating of tube 16.

For starting the hydrocarbon burner, I provide a receptacle 43 supported below 35 the tube 16 which is adapted to hold a suitable liquid fuel such as alcohol, which is burned to supply the initial heat to the tube 16 for raising it to the required temperature to vaporize and preheat the oil.

40 The normal operation of the equipment above described is as follows: The liquid fuel is fed through valve 23 into the heated tube 16 where it is vaporized and expanded in compartment 17 and the vapors are pre- 45 heated in compartment 18. From the latter the heated vapors pass up along passage 26 and through valve 27 into chamber 28 which they mix with the steam or compressed air coming through the valve 29, 50 the resulting mixed fuel thereafter being sprayed and atomized into the furace combustion chamber 10.

In the foregoing description of the apparatus and its operation, no special means 55 have been described for operating the valves and dampers for regulating control thereof, and under ordinary conditions, this requires manual manipulation. An embodiment of the invention will now be described which 60 provides automatic means for efficiently controlling the operation of a hydrocarbon equipment to regulate the steam pressure of boiler 10.

Any conventional type of diaphragm 65 pressure regulator 50 is installed to be op-

erated by the boiler steam pressure in the well known manner with the load carrying portion of arm 50^a extending over and substantially in alignment with the valves 23, 27 and 29, these valves, for simplicity, being preferably arranged in vertical alignment as shown in Figs. 1 and 2. Depending from arm 50^a are preferably two connecting members 51 and 52, one for actuating the valves and the other for the dampers. 70 Thus, the adjustment of each of the connecting members 51, 52, on arm 50^a and hence their vertical movement may be varied independently of the other. 75

As shown in Fig. 2, the lower end of member 51 is secured to a connecting link 53 which is pivoted at its lower portion to a lever arm 23^b, the latter being secured to valve stem 23^a for opening and closing the valves 23 on downward and upward movement respectively of said link 53. The upper portion of said link 53 is pivotally connected to rock arm 27^b of a sector gear rack member 27^c secured to the valve stem 27^a.

A pinion 29^d is secured to the valve stem 29^a and meshes with the gear rack member 27^c for opening and closing said valve 29 in unison with the valves 27. In order to compensate for the reverse turning motion given valve stem 29^a with respect to that given the other valves, the stem 29^a is mounted to turn in the body valve 29^b on the left handed threaded connection 29^c, the coarse pitch whereof gives the proper proportional opening for admitting the steam or compressed air. The connecting link 53 may have a hole 53^a in the lower end thereof on which a weight 54, shown in dotted lines in Fig. 2 may be hung if the weight of connecting member 51 and link 53 are insufficient to positively move the valves 23, 27 and 29 to their closed position on the lowering of arm 50^a.

The lower end of member 52 is secured to the upper end of an inverted U-shaped strap 55, which straddles the valve equipment and is connected at the lower ends thereof to free ends of lever arms 40 and 41 as shown in Fig. 2 for operating the dampers 33, 34.

The control means for the hydrocarbon burner above described may be set to keep the steam pressure at a constant required amount by suitable well known means such as an adjustable spring or weight 50^b on diaphragm regulator 50 as shown in Fig. 3.

The operation of the automatic control means to maintain constant steam pressure is as follows: The lowering of the steam pressure below that required lowers the regulator arm 50^a, which permits the link 53 to move downwardly and simultaneously opens valves 23, 27 and 29 for increasing the feed of fuel and steam or compressed air and to control their mixture. At the same time, 130

strap 55 is permitted to be lowered there-
5 by separating the dampers 33, 34 to expose
more of tube 16 to effectively take care of
the increased amount of oil being fed. On
raising of steam pressure above that re-
quired, the regulator arm 50⁰ is raised and
the automatic control means have the op-
posite effect described above. Thus the
steam pressure is kept practically at the set
10 required amount and the fuel is fed to the
burners properly conditioned for efficient
combustion.

It will thus be seen that there is provided
15 a device in which the several objects of this
invention are achieved and which is well
adapted to meet the conditions of practical
use.

As various possible embodiments might be
20 made of the above invention and as various
changes might be made in the embodiment
above set forth, it is to be understood that
all matter herein set forth or shown in the
accompanying drawings is to be interpreted
25 as illustrative and not in a limiting sense.

Having thus described my invention, I
claim as new and desire to secure by Letters
30 Patent:—

1. A furnace, a liquid fuel burner equipment
35 for said furnace, said equipment hav-
ing regulating valves and a fuel prevapori-
zing portion arranged to receive heat from
the burner of said equipment, an adjustable
damper for regulating the heat to said por-
40 tion, in combination with a control means for
simultaneously opening and closing said
valves and adjusting said damper.

2. In combination, a furnace, a liquid fuel
burner equipment for the furnace, said

45 equipment having regulating valves and a
portion for vaporizing the fuel arranged to
be heated by the burner of said equipment,
an adjustable damper for regulating the heat
to said portion, and control means for sim-
50 ultaneously opening and closing the valves and
adjusting said damper, said means having
lever arms arranged to operate the valves
and a link interconnecting said arms.

3. In combination, a furnace, a liquid fuel
burner equipment for the furnace, said
55 equipment having regulating valves and a
portion for vaporizing the fuel arranged to
be heated by the burner of said equipment,
an adjustable damper for regulating the
heat to said portion, and control means for
60 simultaneously opening and closing the
valves and adjusting said damper, said
means having lever arms arranged to operate
the valves, one of said arms being secured
to a sector rack and pinion for operating
65 one of the valves.

4. A control means for a liquid fuel burner
70 equipment having a fuel preheating portion
comprising a plurality of regulating valves,
separate lever arms for operating some of
the valves, a sector rack secured to one of
said arms, a pinion meshing with said rack
75 mounted to operate one of said valves, a link
interconnecting said arms for simultaneous-
ly regulating all the valves, a damper for
adjustably controlling the heat to said por-
tion and means for operating the damper
concomitantly with the regulation of said
valves.

In testimony whereof I affix my signature.

CHARLES A. ROSIER.
